DESIGN FOR A DRESS

Minna Wuerth, New York, N. Y.

Application August 2, 1941, Serial No. 102,639

Term of patent 3½ years

To all whom it may concern:

Be it known that I, Minna Wuerth, a citizen of the United States of America, residing in New York city, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the dress disclosed of the specific arrangement of the sequins in combination with the tucks on the waist and cuff portions of the dress as shown.

I claim:

The ornamental design for a dress, substantially as shown and described.

MINNA WUERTH.
